MATHIAS DE ZURIK, OF SARTELL, MINNESOTA.

STOCK-CONSISTENCY REGULATOR FOR PAPER MACHINES.

Application filed August 13, 1926. Serial No. 128,986.

This invention relates to an improved apparatus for automatically regulating the consistency of the stock or pulp in paper mills to render it uniform in density before it reaches the paper making machines, thereby causing the resultant paper to be of uniform weight and thickness.

An object of the invention is to provide a stock consistency regulator, comprising members suspended in the flowing stock at different locations, and adapted to be actuated by the movement thereof, each member having a connection with an indicating means whereby the consistency of the stock will be indicated, one of said members having a connection with a source of water supply, whereby, when the stock thickens to a predetermined degree, water will be automatically added and thoroughly intermixed with the stock before it reaches the second member, and conversely, if the supply of stock to the regulator becomes thinner, where it reaches a predetermined degree of thinness, the supply of water thereto will automatically be cut off, thereby causing the stock, as it is discharged from the regulator for delivery to the paper making machine, to be of uniform density, the second member indicating the density of the stock as it is discharged from the regulator.

A further object of the invention is to provide a regulator comprising a structure having a mixing box to which the stock is delivered, and from which it flows over and under a series of baffle plates for thorough mixing, thence through a sieve or grate into a chamber having a member mounted therein adapted to be actuated by the flow and consistency of the stock to automatically add, lessen, or shut off the supply of water to the stock, after which the stock passes through a mixing box or chamber, into a lower chamber also having a member arranged therein, and actuatable by the flow of the stock, to indicate the consistency thereof, before it is discharged from the regulator for delivery to the paper making machine.

A further object is to provide a regulator having a water control device comprising a casing divided by a partition preferably

centrally arranged to form two chambers, one of which has a pipe leading therefrom with its discharge end positioned over the flowing stock, and the other having a waste pipe connecting it with a drain or other receiving means, and a water supply nozzle movably disposed above said partition and actuatable by regulating mechanism controlled by the consistency of the stock to swing the nozzle from one chamber to the other, the partition having preferably an upper knife edge functioning to divide the stream of water from the nozzle, whereby the full stream of water may be discharged into either chamber, or may be divided by the partition and a part caused to enter each chamber, a portion of the water being thus delivered to the stock while the remainder is discharged as waste.

A further object is to provide a stock consistency regulator of simple and inexpensive construction with means for automatically and positively regulating the consistency of the stock.

The particular object of the invention, therefore, is to provide an improved stock consistency regulator for paper making machines.

Other objects of the invention will appear from the following description and the accompanying drawings and will be pointed out in the claims.

The accompanying drawings disclose a structure designed to carry out the various objects of the invention, but it is to be understood that the invention is not confined to the features shown, as various changes may be made within the scope of the claims which follows.

In the drawings:

Figure 1 is a sectional elevation showing the general construction of my improved regulator and also indicating the travel of the stock therethrough;

Figure 2 is a vertical sectional view on line 2-2 of Figure 1;

Figure 3 is a plan view of the structure shown in Figure 1;

Figure 4 is an enlarged detail sectional view on the line 4-4 of Figure 1, showing the water control device;

Figure 5 is a detail sectional view on the line 5—5 of Figure 4, showing the partition in the casing and the movable nozzle disposed thereover;

5 Figure 6 is a horizontal sectional view, on line 6—6 of Figure 4, showing the angular position of the water discharge nozzle with respect to the knife edge of the partition; and

10 Figure 7 is an elevation, partially broken away, of the indicating means.

The improved regulator embodying this invention comprises an elevated mixing box 11 having a feed pipe 12 connected therewith through which the material is fed from a suitable source. An elongated opening 13 is provided in the wall 14 of the mixing box through which the stock or pulp flows by gravity into a relatively smaller chamber 15 having a passage 16 at the bottom thereof through which the material passes as indicated in Figure 1. The material then flows over a sieve or grate 17 through which it is precipitated into a second mixing chamber 20 18. A baffle wall 19 is preferably positioned over the grate 17 and spaced therefrom, as shown, to further increase the mixing of the stock and also to direct it onto the surface of the grate. The material too coarse to pass 25 through the grate, will be discharged onto a board or plate 21 from which it may readily be removed.

From the second mixing box 18, the material flows through an elongated opening 22 30 and into a chamber 23, having a dam 24 at the discharge end thereof, functioning to maintain the stock at a constant depth in the chamber.

Means are provided for adding additional 40 water to the stock in the event that it becomes too thick for the paper making machines by which it is transformed into paper. Such means consists of a member 25 arranged in the chamber 23, that is engaged by the stock 45 as it flows through the chamber. This member 25 is preferably conical in shape, and is supported by means of a cross shaft 26 journaled in bearings secured to the side walls 27 of the chamber 23 (see Figures 1, 2 and 3). An indicator 28, mounted upon and secured to a shaft 29, is connected with the member 25 by means of a connecting rod 31 and crank arm 32 secured to the cross shaft 26, as shown in Figure 3. The indicator 28 50 is preferably offset, as shown in Figure 4, and projects through a curved slot 33 provided in a plate 34 having a mark 35 in the upper portion thereof, which cooperates with the indicator 28 to indicate the consistency of the stock passing through the chamber 23.

60 A water control box 36 is preferably positioned back of the indicator casing 37 and has a partition 38 provided therein, as shown in Figure 5, dividing the interior of the box 65 into two chambers, one of which may be

termed a water supply chamber 39, and the other a waste chamber 41. A pipe 42 leads from the lower portion of the supply chamber 39, and has a nozzle 43 secured to the opposite end thereof which is disposed over the 70 stock at the point where it is discharged from the chamber 23 over the dam 24. (See Figure 1.) A waste pipe 44 is connected to the chamber 41.

A feature of the invention resides in means 75 for automatically controlling the supply of additional water to the stock in the event that it becomes too thick. A discharge nozzle 45 is movably mounted within the control box 36 and normally has its end positioned above the partition 38. This partition, it will be noted, by reference to Figure 5, is preferably provided with a knife edge 46 to divide the stream of water discharged from the nozzle 45 between the two chambers, or to 80 direct it all into either chamber. The nozzle 45 is preferably secured to a relatively larger pipe 47 pivotally connected to a water supply pipe 48 by a pin 49. The pipe connection 47 is preferably larger than the water 85 supply pipe 48, so that the end of the supply pipe 48 may be inserted therein, as shown in Figure 5. By thus supporting the pipe connection 47 and nozzle 45, the latter may be oscillated within the box 36, from one 90 chamber to the other. The position of the nozzle 45 with respect to the partition 38 will regulate the flow of water through the pipes 42 and 44.

95 A forked crank arm 51 is terminally secured to the indicator shaft 29 within the box 36, and engages the nozzle 45, as shown in Figures 4 and 5. Thus when the indicator shaft 29 is partially rotated by movement of the indicator 28, as a result of its connection 100 with the member 25, the position of the nozzle 45 with respect to the edge 46 of the partition 38, will automatically be varied depending upon the consistency of the stock 105 passing through the chamber 23.

110 The member 25 is preferably hollow and is of such size and weight that when the stock is of the proper consistency the indicator 28 will register with the mark 35 provided upon the face plate 34. When the indicator 28 is 115 thus positioned, the water supply nozzle 45 will be disposed over the waste water chamber 41 so that substantially all the water therefrom will be discharged through the pipe 44. If the stock begins to thicken beyond a predetermined degree, the member 25 will be actuated by the stock impinging thereagainst, thereby elevating the depending end thereof with the resultant actuation of the indicator 28 and the nozzle 45. Such 120 actuation of the water supply nozzle 45 by the rising of the member 25 in the stock will cause the discharge end thereof to move towards the water supply chamber 39, thereby 125 causing a portion of the water to flow 130

through the supply pipe 42 and through the nozzle 43 into the moving stock.

The discharge end of the nozzle 43 is preferably elongated so that the stream of water discharged therefrom into the stock will be sheet-like in form. It will also be noted by reference to Figure 6 that the discharge opening in the nozzle 45 is similarly elongated in form, and, that it is arranged at an angle with respect to the knife edge 46 of the partition 38. The purpose of thus angularly arranging the discharge end of the nozzle 45 with respect to the partition 38, is to obtain better regulation of the water. As a result of the elongated opening, the increase in the water supply to the chamber 39 will be gradual, and will be proportionate to the movement of the nozzle as it is moved back and forth over the partition by the action of the member 25, the movement of which is controlled entirely by the consistency or density of the moving stock flowing through the chamber 23.

From the chamber 23 the stock will over-flow the dam 24 and enter a mixing chamber 50, preferably upright in form, and having a series of baffle plates 52, 53 and 54 arranged in staggered relation therein, so as to cause the stock to follow a tortuous path, as it flows by gravity therethrough. Inclined walls 55 are provided between the baffle plates 52 and 53 to cause the stock to be moved inwardly towards the center of the mixing chamber thereby to obtain a better and more uniform mixing thereof.

From the chamber 50 the stock, after having been supplied with additional water, if necessary, is precipitated into a chamber 56, having a dam 57 at the discharge end thereof, over which the stock will flow into a receiving pipe 58 (see Figure 1). A member 59 is disposed within this chamber, adapted to be actuated by the passage of stock therethrough. This member is similarly supported by means of a cross shaft 61, having a crank arm 62 terminally secured thereto, and having a rod 63 connecting it with an arm 64 loosely mounted upon the indicator shaft 29, as shown in Figures 4 and 7. An indicator arm 65, preferably integral with the arm 64, and offset as shown in Figure 4, passes through a slot 66 in the face plate 34 of the indicator casing. The terminal of this indicator arm is adapted to register with a mark 67 upon the face of the plate 34, as shown in Figures 1 and 7. This mark 67 is preferably arranged in vertical alinement with the indicator shaft 29, as shown in Figure 7. The purpose of this indicator is to indicate the consistency of the stock passing through the chamber 56. The member 59 is so adjusted and connected with the indicator arm 65, that when the stock is of the proper consistency, the indicator arm 65 will register with the mark 67. This indi-

cator, therefore, functions to indicate the consistency of the stock before it is delivered to the receiving pipe 58.

When the apparatus is operating under normal conditions, the indicator arm 28 will be actuated very slightly, the member 25 and its connection with the water supply nozzle 45 being adjusted and arranged to supply the necessary quantity of water to the stock to reduce it to the consistency required for the paper making machines. The apparatus, therefore, automatically functions to regulate the consistency of the stock discharged therefrom into the pipe 58, regardless of its consistency when delivered to the apparatus through the supply pipe 12.

Inclined rods or members 68 are preferably arranged in the chambers 23 and 56, at the receiving ends thereof, as shown in Figure 1. These inclined rods or members are preferably disposed in alinement with the members 25 and 59, as shown in Figure 2, and function to divide the stream of stock through the chambers, thereby causing the members to respond more readily to the impinging action of the stock thereagainst, during the operation of the apparatus. The water supply pipe may be suitably supported by means of a bracket 69 secured to an upright bar 71, having its lower portion secured to the rear wall 27 of the upper chamber 23, as shown in Figure 2. The water control box 36 is also preferably supported upon the upright bar 71, as shown in the same figure.

I claim as my invention:

1. In a device of the class described, the combination with a suitable chamber, means for causing a flow of paper stock through said chamber, means for maintaining the stock at a constant level in said chamber, a member movably arranged within said chamber in contact with the flowing stock, whereby the position of said member is varied by changes in the consistency of the stock, means for supplying water to said stock after it passes the movable member, means, controlled by said movable member, for regulating the amount of water supplied to said stock and a discharge passage into which the stock that passes from said chamber is conducted, substantially as described.

2. A device of the class described, comprising in combination, a chamber, means for causing a flow of paper stock through said chamber, a member movably arranged within said chamber in contact with the flowing stock whereby the position of said member is varied by changes in the consistency of the stock, means for maintaining the stock at a constant level in said chamber, a nozzle positioned over said chamber for supplying water to the stock, means controlled by the movement of said member for regulating the amount of water supplied to said

stock, means connected with said member for indicating the consistency of the stock passing through said chamber and a discharge passage into which the stock that passes 5 from said chamber is conducted.

3. A device of the class described, comprising in combination, a chamber having means at one end thereof for delivering paper stock thereto, a dam at the opposite 10 end of said chamber for maintaining the stock at a constant level therein, a member movably mounted within said chamber and in constant contact with the flowing stock whereby the position of said member is 15 varied by the consistency of said stock, a nozzle positioned over the discharge end of said chamber for supplying additional water to the stock, means controlled by the movement of said member for regulating the 20 amount of water discharged from said nozzle into said stock and a discharge passage into which the stock that passes from said chamber is conducted.

4. A device of the class described, comprising in combination, a mixing box having means for delivering a flow of paper stock thereto, a chamber communicating with said mixing box, a dam at the discharge end of said chamber for maintaining the stock at a 25 constant level therein, a member movably mounted within said chamber and in constant contact with the flowing stock whereby the position of said member is varied by changes in the consistency of the stock, a 30 water control device mounted adjacent said chamber and having a nozzle positioned over the discharge end thereof for supplying additional water to the stock, and said member having a connection with said device 35 whereby, when the stock thickens, said member will be operated to actuate said device to supply additional water to the stock, and when it thins, the supply of water thereto will automatically be cut off, thereby causing 40 the resultant flow of stock from said chamber to be substantially uniform in consistency, regardless of its consistency when it enters said mixing box and a discharge conduit for receiving and conducting to the 45 paper machine the stock that passes through said chamber.

5. A device of the class described, comprising in combination, an elongated chamber having an intake and a discharge, means 55 for causing a flow of paper stock through said chamber, means for maintaining the stock at a constant level in said chamber, a member movably mounted within said chamber in constant contact with the flowing 60 stock whereby the position of said member is varied by changes in the consistency of the stock, a water supply device having a discharge nozzle positioned adjacent the discharge end of said chamber, said device 65 having a connection with said member

whereby, when the stock thickens, said member will operate said device to deliver additional water to said stock through said nozzle, and when the supply of stock to said chamber becomes thinner, said member will 70 operate to cut off the supply of water thereto, and means for indicating the consistency of the stock after having passed through said chamber and a discharge conduit in which the stock that passes from said chamber is received for passage to the paper machine.

6. The combination with a device of the class described, including a chamber having means for causing a flow of paper stock 80 therethrough, means for maintaining the stock in said chamber at a constant level, of a member movably mounted within said chamber and responsive to changes in the consistency of the flowing stock, a water supply device having a discharge nozzle positioned adjacent the discharge end of said chamber, said device comprising a casing having a partition disposed therein and dividing it into two compartments, a water 85 supply pipe movably mounted within said casing over said partition, and said supply pipe having a connection with said member whereby, when the member is actuated by changes in the consistency of the stock, said supply pipe will be operated within said casing to deliver additional water to said stock when it becomes too thick, and to cut off the supply of water thereto when the stock delivered to said chamber reaches a predetermined degree of thinness and a discharge 90 conduit for receiving and conducting to the paper machine the stock that passes through said chamber.

7. In a stock consistency regulator for 105 paper machines, a chamber for passage of stock on its way to a paper machine, means for conducting paper stock to said chamber, means for maintaining the stock in said chamber at a constant level, a member suspended in the flowing stock in said chamber and actuatable by the consistency of the stock, an indicator operatively connected with said member for indicating the consistency of the stock in said chamber, said member being 110 also connected with a water supply control arranged to supply water to the stock after it passes from said chamber and a discharge conduit for receiving and conducting to the paper machine the stock that passes through 115 said chamber.

8. In a stock consistency regulator for paper machines, a plurality of chambers and a conduit connecting the discharge of the first chamber with the inlet of the second chamber, means for maintaining the stock in each chamber at a constant level therein, means arranged in each chamber and in contact with the flowing stock therein for indicating the consistency of the stock in such 120 125 130

chamber and means actuated by the member in the first chamber for controlling the discharge of water into the stock during its passage from the first to the second chamber.

the stock has finally passed through the 35 chamber whereby the consistency of the stock is only indicated before the water supply is added thereto.

5 9. In a stock consistency regulator for paper machines, a plurality of chambers and a conduit connecting the discharge of the first chamber to the inlet of the second chamber, said conduit being provided with means for 10 mixing the stock as it passes therethrough and each of said chambers being provided with means for maintaining the stock at a constant level in said chamber, means for conducting stock to the first chamber and a 15 discharge conduit for receiving and conducting to the paper machine the stock that passes from the second chamber, means arranged in each chamber and in contact with the flowing stock therein for indicating the 20 consistency of the stock in such chamber and means actuated by the member in the first chamber for controlling the discharge of water into the stock during its passage from the first to the second chamber.

11. Means for supplying, regulating and indicating the consistency of stock supplied 40 to a paper making machine comprising a container through which the stock passes, mechanism moved in accordance with the consistency of the stock, a water supply controlled by said mechanism said water supply 45 communicating with the stock after it has finally passed said mechanism, and a second mechanism moved by the stock after the water has been introduced into the stock for indicating whether or not the stock is of 50 proper consistency after the water has been introduced therein.

25 10. Means for supplying stock to a paper making machine and regulating the consistency thereof comprising a container through which the stock passes only once in the normal operation of the device said container including a chamber with mechanism the 30 movements of which are broadly controlled by the consistency of the stock, a water supply controlled by said mechanism, said water supply emptying into the stock only after

12. Means for regulating the consistency of stock as it passes to a paper making machine comprising a container through which the stock passes, a water supply for the stock, mechanism controlled by the consistency of the stock for regulating the water supplied to the stock, an indicator for visibly indicating the consistency of the stock controlled by 55 said mechanism, a second mechanism for indicating the consistency of the stock after the water supply has been introduced into the stock, and a visible indicator operated by said second mechanism.

In witness whereof, I have hereunto set my hand this 2nd day of August, 1926.

MATHIAS DE ZURIK.
